UNITED STATES PATENT OFFICE.

ISAK WEISENFREIND, OF NEW YORK, N. Y.

DESIGN FOR AN URN.

Application filed January 18, 1926. Serial No. 16,149. Term of patent 3½ years.

To all whom it may concern:

Be it known that I, ISAK WEISENFREIND, a citizen of the United States, and a resident of the borough of Manhattan, city, county, and State of New York, have invented a new, original, and ornamental Design for an Urn, of which the following is a specification.

The design is illustrated in the accompanying drawing in which:

I claim:

The ornamental design for an urn, as shown.

In witness whereof I have hereunto set my hand at the city, county and State of New York, this 16th day of January, 1926.

ISAK WEISENFREIND.
